US0D1028894S

(12) **United States Design Patent** (10) Patent No.: **US D1,028,894 S**
(45) Date of Patent: ** May 28, 2024

(54) **BATTERY BOX**

(71) Applicant: **MicrovastPower Systems Co., Ltd.**,
Huzhou (CN)

(72) Inventors: **Yang Wu**, Zhejiang (CN); **Ningqiang Xiao**, Zhejiang (CN); **Heng Zhao**, Zhejiang (CN); **Wenjuan Liu Mattis**, Zhejiang (CN)

(**) Term: **15 Years**

(21) Appl. No.: **35/516,365**

(22) Filed: **Aug. 3, 2022**

(80) **Hague Agreement Data**

Int. Filing Date: **Aug. 3, 2022**

Int. Reg. No.: **DM/226762**

Int. Reg. Date: **Aug. 3, 2022**

Int. Reg. Pub. Date: **Feb. 24, 2023**

(51) **LOC (14) Cl.** 13-02

(52) **U.S. Cl.**

USPC **D13/119**
